(57) **CLAIM**

The ornamental design for a mat for toilet plunger, as shown and described.

DESCRIPTION

The U.S. patent application Ser. No. 15/174,768, filed Jun. 6, 2016, is hereby incorporated by reference.

FIG. 1 is an exploded perspective view of the mat for toilet plunger according to one embodiment of my new design; FIG. 2 is a top plan view thereof;

FIG. 3 is a front elevation view thereof, the back, left side, and right side elevation views being the same;

FIG. 4 is a bottom plan view thereof; and

FIG. 5 is a center section view thereof.

FIG. 6 is an exploded perspective view of the mat for toilet plunger according to a second embodiment of my new design;

FIG. 7 is a top plan view thereof;

FIG. 8 is a front elevation view thereof, the back, left side, and right side elevation views being the same;

FIG. 9 is a bottom plan view thereof; and,

FIG. 10 is a center section view thereof.

The dashed lines shown in the drawings illustrate environmental structure and form no part of the claimed design.
